US00D571024S

(12) **United States Design Patent** (10) Patent No.: **US D571,024 S**
Lee (45) Date of Patent: ** Jun. 10, 2008

(54) **GRID STRUCTURE FOR STABILIZATION
OF GRASS, TURF OR PARTICULATE
MATERIAL**

(76) Inventor: **Alan Sian Ghee Lee**, 21 Almond Crescent, Singapore 677779 (SG)

(**) Term: **14 Years**

(21) Appl. No.: **29/231,113**

(22) Filed: **Jun. 1, 2005**

(51) **LOC (8) Cl. 25-99**

(52) **U.S. Cl. D25/199; D25/118**

(58) **Field of Classification Search** D25/114-116, D25/118, 199, 152; D21/485, 494; 52/180, 52/181, 318, 384, 387, 448, 581, 660, 663, 52/393; 47/33; 404/32, 34-36, 40-42, 7, 404/8, 134; 428/44, 52, 53, 99; D23/261, D23/202, 138

See application file for complete search history.

(57) **CLAIM**

The ornamental design for a grid structure for stabilization of grass, turf or particulate material, as shown and described.

DESCRIPTION

FIG. 1 is a perspective view of a grid structure for stabilization of grass, turf or particulate matter showing minute design;

FIG. 2 is a top plan view;

FIG. 3 is a bottom plan view;

FIG. 4 is a rear view;

FIG. 5 is a left side view; and,

FIG. 6 is a right side view, the front view being a mirror image.
